UNITED STATES PATENT OFFICE.

GEORGE W. GRAHAM, OF EDMORE, NORTH DAKOTA.

DESIGN FOR A TELEPHONE OR TELEGRAPH CUP.

48,590.

Specification for Design.

Patented Feb. 22, 1916.

Application filed January 27, 1915. Serial No. 4,802. Term of patent 14 years.

To all whom it may concern:

Be it known that I, GEORGE W. GRAHAM, a citizen of the United States, residing at Edmore, in the county of Ramsey and State of North Dakota, have invented a new, original, and ornamental Design for Telephone or Telegraph Cups, of which the following is a specification, reference being had to the accompanying drawing, forming part thereof.

Figure 1 is a view in elevation of a tele-

phone or telegraph cup, showing my new design, Fig. 2 is a view in elevation taken at right angles to Fig. 1 of my new design.

I claim:

The ornamental design for a telephone or telegraph cup, as shown.

GEORGE W. GRAHAM.
